PICKUP DIVIDER ATTACHMENT FOR GRAIN BINDERS

Frank J. Betz and Michael A. Betz, Gaza, Iowa

Application April 12, 1940, Serial No. 329,330

4 Claims. (Cl. 56—314)

Our invention pertains to a device usable principally with grain binders or harvesting machines.

An object of our invention is to provide a divider attachment as well as a guard for the cutter bar of a binder etc.

A further object of our invention is to provide an attachment which breaks away tangled growths and which includes efficient means for attachment of the arrangement to the binder platform.

A further object of our invention is to provide divider attachments or guards which will cover a substantial width of the cutter bar, leaving only certain areas for cutting purposes.

A further object of our invention is to provide means for attachment of the arrangement to the standard guard members of the reciprocating cutter and to provide means for conveying the grain downwardly on to the moveable platform of the binder etc.

A further object of our invention is to provide the above mentioned features in a construction which is simple to manufacture.

With these and other objects in view, our invention consists in the construction, arrangement and combination of the various parts of our device, whereby the objects contemplated are attained, as hereinafter more fully set forth, pointed out in our claims, and illustrated in the accompanying drawing, in which:

Figure 1 is a plan view of a portion of a binder platform below the reel thereof showing the attachment of our device.

Figure 2 is a sectional view taken substantially along the lines 2—2 of Figure 1.

Figure 3 is a sectional view taken substantially along the lines 3—3 of Figure 2.

Figure 4 is a fragmentary section taken along the lines 4—4 of Figure 3.

Figure 5 is a sectional view of a modification taken along the lines 5—5 of Figure 6, and

Figure 6 is a section taken along the lines 6—6 of Figure 5.

In harvesting soy beans and similar crops, the overhanging stalks will usually hang together and will block the cutting sickle and guards since they tangle in the same. To guard against this, provide a certain device which will spread the entangled portions apart so that the cutting operation will proceed uniformly.

We also provide a guard which will suitably cover or block certain groups of cutter members so that only those cutters positioned in the line of travel or in the row itself will do the actual

cutting. We have used the character 10 to designate the usual traveling belt platform of a binder which is suitably journaled within the side members 11 and 12 and which rests upon a platform 13. Attached adjacent to the platform 13 is a channel 14 upon which is mounted the reciprocating sickle 15 which moves within the pointed guard members 16, the entire arrangement of which is attached to the bar 17.

19 The divider attachment or the guards are indicated by the character 18 and include the forward downwardly sloping portions 19 and the rearward downwardly sloping portions 20 which rear portions 20 terminate above the member 11. 15 The forward end of the guards 18 include the rounded nose 21 and the guards 18 include side bevelled portions 22.

Attached at 23 to the portion 18 is the member 24 to which is attached at 25 the angle member 26 having the vertical portion 27. Spaced transversely and at equal intervals along the vertical portion 27 are a series of openings 28 which are adapted to receive the points of the guards 16 which extend therethrough as shown in Figure 2. Since the guards 16 taper, they can be placed into these openings up to the maximum thickness accommodating the same which will assist to hold the member 18 in rigid position. A further angle member 29 is rigidly attached to the vertical portion 27 and includes the lower flange 30 which lower flange includes a series of openings 31. Received through two of the openings 31 is the U bolt 32 into which is received the lengthened rod 33.

35 The rod 33 extends into the upwardly inclined portion 34, thence into the vertical portion 35 and thence into the further horizontal portion 36 which is pivotally attached at 37 to the portion 19 of the member 18. The rear end of the rod 33 40 extends into the portion 38 which is attached to a further substantially U shaped member 39 having ends received at 40 through the cross plate 41, which is attached to the fixed portions 42 of the binder.

45 The ends 43 of the member 39 are threaded and receive the nuts 44 thereon. It will be seen from the foregoing construction that the guard 18 is supported and rests upon the sickle guards 16 and when the nuts 44 are drawn up on the U bolt 39, the entire arrangement is securely clamped against the base member 13 and the guards so that in effect a rigid structure is provided. The character 45 represents the usual wheel structure supporting the unit, and it will

be understood that the reel is not shown for clearness in understanding the structure.

Usually within the transverse limits of the base member 13 or within the space 46 there are bars or other supporting structure which must be cleared with our arrangement in order to clamp the guards. To effect this result, we provide the aforesaid pivotal attachment at 37 which will allow positioning of the clamping bar 33 to one side or the other to pass such obstructions. The flange 30 or the angle 29 permits such lateral adjustment since the ends of the U bolt 32 can be placed in any pairs of openings with the arrangement in Figures 3 and 4 being in the center pair.

The U bolt arrangement, however, can be placed in the central and extreme right hand openings or the central and extreme left hand openings as shown in Figure 4 to permit such lateral adjustments. The openings in the transverse plate 41 can also be formed in the same manner to permit of this adjustment.

As the machine travels in the direction of the arrow 47, it will be noted that the bend between the portions 34 and 35 on the rod 33 provide a runner effect to allow the easy passage through the field. The nose 21 also provides this feature and the further portions 48 adjacent the nose 21 are rounded to allow passage through the stalks in a simple and efficient manner. It will be seen from Figure 1 that as the machine travels forwardly, it will be noted that the guards 18 block off certain portions of the sickle arrangement leaving only those widths at 49 which will cut the stalks.

Meanwhile, during progress of the machine, however, the guard members 18 are separating the tangled growths which pass smoothly over the smooth contours of the guards. Also the cut material which is handled by the sickles will pass on to the moving platform 10 and the downwardly extending portions 20 of the guards 18 will have the tendency to allow the cut grain to travel down the incline which is adjacent to the guards so that as a result, the guards concentrate the cutting only to the rows desired and permit passage of material uniformly.

It will be understood that the portions 49 will travel along the rows to be cut so that in this manner, the spacing can also be as desired.

A further preferred modification of our arrangement is shown in Figures 5 and 6 in which most of the same features are employed as heretofore described with the exception, however, that instead of providing openings in the vertical member 27, the spacing members 50 are provided each of which include the pairs of openings 51.

A pair of spacers 52 (see Figure 5) are positioned between the members 50 and the flange 27 through which passes the bolts 53. In this form of structure the pointed guards 16 will pass through openings 51 but will not penetrate through the portions 27 but will abut thereagainst and will be further supported by the openings 51. This permits of more convenient adjustment. If desired, the bolts can pass through the slotted arrangement as shown by the dotted structure at 54 in Figure 6 to permit for horizontal adjustment and vertical slots can be provided if necessary in the flange 27 to permit of vertical adjustment. Small openings are provided at 55 in the member 29 to receive the ends of the guards 16.

By virtue of this structure, only the two outer

sickle guards need be employed for the bracing and supporting function, with the remainder of the guards resting against the flange 27. This arrangement is preferred since it allows for more convenient adaptation to sickle guards without fixing of too many centralized points as required by the structure shown in Figure 3 and permits more convenient adjustment as explained. The guards 18 terminate in vertical sides 26 to protect against stalks along the sides of the rows.

The guards 18 can be removed and replaced on any series of sickle guards and in harvesters or any structure not utilizing sickle guards, a pair of braces such as indicated by the character 57 in Figure 1 can be clamped beneath the platform to secure the guards.

It will now be seen that we have provided an attachment for grain binders and similar machines which acts as a guard for the cutting members, which breaks away tangled stalks and the like, which can be adjusted laterally, and which includes means for efficient clamping of the divide heads on to such machines. It will be seen further that we have provided an arrangement which can be manufactured simply.

Some changes may be made in the construction and arrangement of the parts of our invention without departing from the real spirit and purpose of our invention, and it is our intention to cover by our claims any modified forms of structure or use of mechanical equivalents, which may be reasonably included within their scope.

We claim as our invention:

35. 1. In combination with a grain binder and the traveling belt thereof comprising a tapering head member, said member diverging rearwardly toward the binder platform, and including a transverse flange having openings adapted to receive tapered sickle guards, means for bracing said head member against the platform, said head including a forward sloping portion and a rearward sloping portion, said rearward portion positioned adjacently to the binder traveling belt.
40. 2. In combination with a grain binder and the traveling belt thereof comprising a tapering head member, said member diverging rearwardly toward the binder platform, and including a transverse flange having openings adapted to receive tapered sickle guards, means for bracing said head member against the platform, said head including a forward sloping portion and a rearward sloping portion, said rearward portion positioned adjacently to the binder traveling belt, a rod pivoted to said head member and extending beneath the binder platform, a U bolt brace receiving said rod and attached to said transverse flange, means for permitting lateral shifting of said rod including a further flange member attached to the flange having a plurality of openings receiving the ends of said U bolt brace.
45. 3. A divider and guard attachment for binders comprising a substantially triangular shaped head member having rearwardly diverging sides, said member including a transverse flange, against which the binder sickle guards are adapted to rest, a pair of plates having openings spaced from said flange adapted to receive certain of said sickle guards, means for maintaining said plates in fixed spaced relation from said flange, means for bracing said head member against the binder platform including a rod pivoted to said head member and extending beneath the binder platform, means for attaching said rod rearwardly of said platform, including U

bolts attached to the rear end of said rod, a keep plate receiving said U bolts, the ends of said U bolts being threaded, nuts being engaged therewith, a U bolt brace receiving said rod and attached to said transverse flange.

4. In combination with a grain binder and the traveling belt thereof comprising a substantially triangular shaped head member having the base of the triangle thereof positioned over a plurality of sickle guards, means for clamping the base portion thereof to the sickle guards, a bracing rod pivoted to the head member and extending beneath the binder platform, means for clamp-

ing said rod against the rear end of the binder platform, said head member including a transverse flange, a pair of plates having openings spaced from said flange, said openings adapted to receive tapered sickle guards, means for maintaining spacing of said plates from said transverse flange in fixed relation, said head member including a forward sloping portion and a rearward sloping portion, said rearward portion positioned adjacently to the binder traveling belt.
